DESIGN FOR A DOOR FOR A DOMESTIC WATER HEATER OR THE LIKE

Clarence H. Morrow, Shaker Heights, Ohio, assignor to The Hotstream Heater Company, Cleveland, Ohio, a corporation of Ohio

Application May 26, 1938, Serial No. 77,400

Term of patent 7 years

To all whom it may concern:

Be it known that I, Clarence H. Morrow, a citizen of the United States and a resident of Shaker Heights, in the county of Cuyahoga and State of Ohio, have invented a new, original, and ornamental Design for a Door for a Domestic Water Heater or the Like, of which the following is a specification, reference being had to the accompanying drawing, forming a part thereof.

In said drawing, Fig. 1 is a front view of a door for a domestic water heater or the like showing my new design; Fig. 2 is a top plan view thereof; and Fig. 3 is a side view thereof.

I claim:

The ornamental design for a door for a domestic water heater or the like, as shown.

CLARENCE H. MORROW.
